UNITED STATES PATENT OFFICE.

GEORGE W. STOCKMAN, OF INDIANAPOLIS, INDIANA, AND JOHN R. DUFFIN,
OF DECATUR, ILLINOIS; SAID DUFFIN ASSIGNOR TO EDWARD L. THOMAS.

PRESERVING FURS, FEATHERS, CLOTHING, CARPETS, &c., FROM MOTHS, MILDEW, &c.

SPECIFICATION forming part of Letters Patent No. 269,134, dated December 12, 1882.

Application filed May 29, 1882. (No model.)

To all whom it may concern:

Be it known that we, GEORGE WASHINGTON STOCKMAN and JOHN ROLAND DUFFIN, citizens of the United States, residing respectively at Indianapolis, in the county of Marion, State of Indiana, and Decatur, in the county of Macon, State of Illinois, have discovered certain new and useful improvements in preserving furs, feathers, clothing, carpets, woolens, silks, 10 velvets, and other fabrics that are subject to damage from moths, mildew, dampness, folding, and light; and we do hereby declare that the following is a full, clear, and exact description of the invention or discovery, which will 15 enable those skilled in the art to which it appertains to make and use the same.

Heretofore furs, feathers, velvets, clothing, and other fabrics subject to damage from moths, mildew, dampness, folding, and light have 20 been preserved in various ways and by several processes, of which we cite, for example, those now in use among the furriers of the United States and France, which are briefly as follows, to wit: To keep furs during the summer they are thoroughly cleaned and dusted, placed in air-tight boxes, and stored away for a few weeks, and in the case of delicate goods for only a few days, when they are again dusted by beating, for the purpose also of relieving 25 the fur from the effects of heat or sweating, aired, replaced in the hermetically-sealed boxes, and stored again for a few days or weeks, when the process of beating and airing is again repeated, and thus until summer ends. Drugs 30 such as tar, camphor, cedar-chips, and tobacco are sometimes employed for the protection of small quantities and common goods; but these are not only unreliable, but damage the goods by their offensive odor, while under the 35 beating process the goods are worn by friction, faded by light, and deadened by heat, and in case of silk fur-lined articles they are injured by the creases which result from folding.

There are other inferior processes, such as 40 cedar closets, chests, &c.; but these furnish only partial protection from worms, and provide no relief from the effects of heat.

Moths destroy furs, feathers, and fabrics by 45 eating, light by fading, heat by deadening and 50 decaying, dampness by rotting and develop-

ing mildew, and until the present we know of no single process which is a safe and satisfactory protection against all of these evils.

The object of our process is thoroughly to 55 preserve during the summer months from damage by moths, worms, vermin, fading, mildew, and the effects of heat, furs, feathers, clothing, carpets, woolens, silks, velvets, and other fabrics subject to injury from said causes, without detracting from the value of said goods; and 60 to this end our discovery or process consists in the application of cold dry air, in a dark storage-room with dead-air-space walls, to the goods treated.

To carry our invention or process into effect 65 we construct a storage-room with double walls, leaving a dead-air space between the layers of the wall, filling said space with charcoal or some similar substance, and reduce the temperature of said room by refrigeration to 32° 70 to 35° Fahrenheit by means of any convenient refrigerating process or machinery which will dry the air it cools. Of such machines or processes we may use the Stockman-Stephens 75 patent. We locate our refrigerator at or near the top of the room to be cooled, and as the air above is cooled it falls through the lighter and warmer air to the lower part of said room, forcing the warm air into the vicinity of the refrigerator, where it is cooled, 80 and in its turn falls through the air below, by this means evolving a current of air, which, as is a well-known fact, carries all the moisture to the pans or tanks of the freezing machinery, 85 where it is deposited in the shape of common frost. By these means we obtain a cold dry air of any desirable temperature, which may be placed at about 38° Fahrenheit to answer the demands of our process. The walls of the storage-room are blind, or without windows, 90 and the room is therefore dark. By reducing the temperature to 38° Fahrenheit we render it impossible for moths, worms, or vermin to develop or be active, destroy mildew or any of the fungi, and keep furs in a lively and healthy 95 condition. By rendering the room dark, or, rather, by excluding the light, we preserve the color of all goods, and as we keep the temperature of the entire room down to 38° Fahrenheit or below during the whole summer, we 100

may hang or store goods in bulk in any part of said room, and hence we avoid the effects of folding, as boxes are not required.

The results obtained by the use of cold air in a dark storage-room may be stated as follows, to wit: Moths and other vermin are prevented from developing or acting, goods will not fade, furs will not become flat or dead, no form of fungi can exist, and the effects of dampness and heat, of folding and friction, are avoided.

We claim no novelty in the form or character of the refrigerator or storage-room, as any dark room with dead-walls and any refrigerating process which will produce a dry cold temperature will meet the demands of our process.

Having described our process, what we claim, and desire to secure by Letters Patent, is—

1. In the preservation of furs and other goods subject to injury from moths, the process of preventing damage to such goods from moths by the use of refrigerated dry air, as described.

2. The process of preserving the life and color of furs and fabrics by means of cold dry air in a dark storage-room, all substantially as described.

GEORGE WASHINGTON STOCKMAN.
JOHN ROLAND DUFFIN.
